REFRIGERATING APPARATUS

Richard E. Gould, Dayton, Ohio, assignor to General Motors Corporation, Dayton, Ohio, a corporation of Delaware

Application August 31, 1935, Serial No. 38,799

4 Claims. (Cl. 154—45)

This invention relates to refrigerating apparatus and more particularly to insulating means for refrigerator cabinets.

Heretofore, most insulating units for refrigerator cabinets have been heavy and thus difficult to handle or they have been light and fragile, and, therefore, likewise difficult to handle.

It is an object of my invention to provide an insulating unit which is easy to handle, and which will withstand rough handling without damage, and also be capable of being inserted in place and fitting tightly therein without difficulty.

It is a more specific object of my invention to provide an insulating unit of spaced sheets having resilient spacing structures extending around the edges of the sheets provided with sufficient resiliency to make sealing engagement with the adjacent spaced sheets and spacing structures so as to provide substantially sealed air spaces between the sheets and providing sufficient resiliency to enable the unit to be compressed slightly when being inserted into the insulation space and thereafter to expand to tightly engage the walls of the insulation space.

Further objects and advantages of the present invention will be apparent from the following description, reference being had to the accompanying drawing, wherein a preferred form of the present invention is clearly shown.

In the drawing:

Fig. 1 is a fragmentary vertical sectional view of a refrigerator cabinet provided with insulating units embodying my invention;

Fig. 2 is a fragmentary sectional view of an upper corner of the cabinet shown in Fig. 1;

Fig. 3 is a plan view of a corner of one of the resilient frames forming the spacing structure;

Fig. 4 is a view in elevation of the spacing structure taken from the right of Fig. 3; and

Fig. 5 is a view in elevation of a corner of one of the spacing structures looking from the bottom of Fig. 3.

Generally speaking, my insulating unit comprises a plurality of slab-like units which are stacked together within an enclosing envelope which forms an outer seal. Each of these slab-like units is formed of a resilient rectangular frame structure comprising four strips of double asphalt paper which are jointed at their end portions to form a rectangular structure. This rectangular structure is formed into a resilient spacing structure by turning up the outside edges of the strips so that an acute angle is made with the flat portions of the strips. To the wide flat

side of this rectangular frame so formed is fastened by an adhesive such as asphalt either a foil or a paper sheet. The foil preferably should be of bright aluminum or zinc, each of which has the property of reflecting radiant heat to a relatively high degree.

Referring now more particularly to the drawing, there is shown in Fig. 1, a refrigerator cabinet generally designated by the reference character 20 provided with inner metal walls 22 enclosing the food compartment 24 and outer metal walls including side walls 26 and top and bottom walls 28 and 30 which are spaced from the inner metal walls 22 to provide insulation space therebetween. Within the insulation space, there are provided insulating units such as the insulation units 32 in the side walls and the insulation units 34 and 36 in the top and bottom walls.

These insulating units are similar in construction and shape and for this reason one of the insulating units 34 is taken as an example of the construction of these units. The insulating unit 34 is made up of a plurality of slab-like units 36. Each of these slab-like units comprises a rectangular frame structure generally designated by the reference character 38 which is formed of strips of heavy resilient paper, preferably paper made up of a plurality of layers with asphalt in between the layers. These strips are doubled as best shown by the strip 40 in Fig. 5. After the four strips are doubled, they are placed in the form of a rectangle and fastened together at the corners by a staple 42 as best shown in Figs. 3, 4 and 5, or by a suitable adhesive such as asphalt. If desired, both the staple and the asphalt may be used. The corners are then cut off on a 45° angle and the outer edges of the strips turned up as shown at 44 and 46 to form a cantilever projection extending from the wide flat portion of the strip at an acute angle. This makes a sort of a V-shaped section. This cantilever projection is highly resilient and when compressed, will return substantially to its original shape. Upon the bottom side of each of these frames, I fasten by a suitable adhesive such as glue, either a sheet of paper or some heat reflecting foil or composition sheet such as aluminum or zinc foil. This completes the assembly of one of the slab-like units.

The slab-like units of each insulating unit may be made all alike upon one machine. However, it is desirable that about two or three of these slab-like units be provided with a heat reflecting surface and in order to reduce the cost that the remainder of slab-like units have a paper

sheet which is relatively impervious to air. Preferably, the slab-like units provided with heat reflecting sheets are placed in between two pairs of slab-like units provided with paper sheets. 5 These slab-like units, preferably from four to seven in number, are placed within a waterproof envelope 48 which may be formed of a plurality of layers of paper with asphalt in between. This envelope is then closed and sealed.

10 Preferably, the envelope is just as large and may even be slightly larger than the insulation space provided within the walls of the cabinet. Thus, in placing the envelope within the cabinet, it may be compressed slightly and when in place 15 will fit tightly against the walls of the cabinet, due to the resiliency provided in the rectangular frames of the slab-like units. The cantilever projecting edge portions with their own resiliency keep in contact with the adjacent slab-like unit 20 and form an air seal around the air space between the sheets of paper and foil. Thus, an insulating unit of a plurality of sheets of foil and paper with enclosed air spaces therebetween is provided.

Because of the resilient frame construction, the 25 insulating unit may be compressed to a considerable degree and yet return substantially to its original shape. Inasmuch as thin light weight material is used, the insulating unit is relatively low in weight. The periphery of the insulating 30 unit is guarded by the turned-up edges of the frame members and since the frame members are resilient, the insulating unit may be grasped along the edge portions without damage. Likewise, the 35 resiliency of the unit is valuable, since it enables the unit to accommodate itself to variable dimensions of insulating space and yet fit tightly therein. The materials of which the insulating unit is made are all relatively low in cost, and the structure may readily be made by automatic 40 machines. While the insulating unit has been shown as applied to refrigerator cabinets, it may also be used to serve other insulating purposes.

While the form of embodiment of the invention as herein disclosed constitutes a preferred form, 45 it is to be understood that other forms might be adopted, all coming within the scope of the claims which follow.

What is claimed is as follows:

1. An insulating structure including a plurality 50 of slab-like units formed of a polygon-shaped sheet portion having resilient spacing structures extending parallel to and along the outer edges of the polygon-shaped sheet portion, said resilient

spacing structures being capable of being compressed and returning to substantially their original shape through their own resiliency, said spacing structures being generally V-shaped in cross section and formed of a resilient sheet material, said slab-like units being stacked upon one another to form an insulating unit. 5

2. An insulating structure including a plurality of slab-like units formed of a polygon-shaped sheet portion having resilient spacing structures extending parallel to and along the outer edges of the polygon-shaped sheet portion, said resilient spacing structures being capable of being compressed and returning to substantially their original shape through their own resiliency, said spacing structures being formed of cantilever sheet portions extending at an acute angle to the polygon-shaped sheet, said slab-like units being stacked together to form an insulating unit. 10 15

3. An insulating structure including a plurality of slab-like units formed of a polygon-shaped sheet portion having resilient spacing structures extending parallel to and along the outer edges of the polygon-shaped sheet portion, said resilient spacing structures being capable of being compressed and returning to substantially their original shape through their own resiliency, said spacing structures including flat resilient strip material in units joined together at their adjacent 20 25 ends to form a polygon-shaped structure, said strip material having a longitudinal edge turned up and back to form an acute angle, said turned up edge portion forming a resilient cantilever, and an envelope enclosing said slab-like units and holding said units in a compressed condition 30 35 therein.

4. An insulating structure including a plurality of slab-like units formed of a polygon-shaped sheet portion having resilient spacing structures extending parallel to and along the outer edges of the polygon-shaped sheet portion, said resilient spacing structures being capable of being compressed and returning to substantially their original shape through their own resiliency, said spacing structures including flat resilient strip material in units joined together at their adjacent 40 45 ends to form a polygon-shaped structure, said strip material having a longitudinal edge turned up and back to form an acute angle, said turned up edge portion forming a resilient cantilever, said spacing structures being formed of a doubled over strip of asphalt paper. 50
